UNITED STATES PATENT OFFICE.

VICTOR HEINZE, OF CHICAGO, ILLINOIS.

MEANS FOR CORRECTING THE HUMAN HAND FOR MUSICAL PURPOSES.

1,204,437.

Specification of Letters Patent.

Patented Nov. 14, 1916.

Application filed April 17, 1915. Serial No. 22,135.

To all whom it may concern:

Be it known that I, VICTOR HEINZE, a citizen of the United States, and a resident of the city of Chicago, in the county of Cook and State of Illinois, have invented a certain new and useful Improvement in the Means for Correcting the Human Hand for Musical Purposes; and I do hereby declare that the following description of my 10 said invention, taken in connection with the accompanying sheets of drawings, forms a full, clear, and exact specification, which will enable others skilled in the art to which it appertains to make and use the same.

15 My invention relates generally to improvements in the method of, and means for correcting the human hand for musical purposes, and it consists, essentially, in the novel and peculiar combination of parts 20 and details of construction, as hereinafter first fully set forth and described and then pointed out in the claims.

In the drawings already referred to, which disclose my invention more fully, 25 Figure 1 is a plan thereof, certain parts being broken away and others shown in horizontal section for clearness of detail. Fig. 2 is an end elevation of Fig. 1. Fig. 3 is a rear elevation of Fig. 1. Fig. 4 is a plan of 30 a fragment of the device, illustrating the means whereby the thumb or first finger of a hand is corrected into a faultless member as hereinafter described. Fig. 5 is a vertical transverse section in line 5—5 of Fig. 4, 35 with certain elements of the structure eliminated. Fig. 6 is a section of a detail in line 6—6 of Fig. 2. Fig. 7 is a horizontal section in line —7— of Fig. 5. Fig. 8 is a like section in line 8—8 of Fig. 5. Fig. 9 40 is an edge view of a ring and attaching chain employed for correcting the thumb and the fingers of a hand, by means of my invention. Fig. 10 is a plan view thereof, and Fig. 11 is a side view of an elastic band 45 used in connection with fingers. Fig. 12 is an elevation of concave sleeves for use in connection with the palm of the hand. Figs. 13 and 14 are a plan and an elevation of rings adapted to pass over the fingers of 50 the musical student. Fig. 15 is a diagrammatic view of a portion of my device show-

ing a finger in position for strengthening the flexor muscles at the third joint thereof, while Fig. 16 indicates the same finger with the extensor muscles undergoing the 55 strengthening process. Fig. 17 indicates the second joint as under extensor muscle strengthening, and Fig. 18, the same joint as under treatment for the flexor muscles.

Like parts are indicated by corresponding 60 symbols or characters of reference in all the figures of the drawings.

A fact long known to music masters, the great importance of which is becoming more recognized every day, is that the student of 65 instrumental music, no matter how great his natural or latent talent may be, must in order to become a finished player of the piano or any other stringed musical instrument, acquire a faultless, sure, and never 70 failing technique, to acquire which, the student must possess what is commonly known as a good piano or violin hand. By 75 hand I mean the fingers, palm, and wrist, and, faultless hands must be well constructed for the purpose intended and possessed of the necessary muscular strength in the hands as well as in the arms.

Few students of the piano or other stringed instruments are endowed by nature with good, properly constructed hands; possessed of the necessary muscular strength, to naturally develop into proper condition; in other words "faultless" hands are the exception, rather than the rule. A faulty 80 hand may be characterized by being too narrow in the palm; the metacarpals being spaced too closely together, so that the third digit or finger tips have insufficient separation between them. Another characteristic 85 is the lack of muscular strength, or that the flexor or extensor, and the multiplicity of other muscles controlling the functions of the hand are too hard, too stiff, or too closely interlaced; that there is a painful lack of 90 pliability, flexibility, and elasticity of the muscular group governing and connecting the first digit of the fingers of the hand at or near the palmar joints, and that there exists too great a sympathetic movement between the fingers of the hand. The conditions existing in such a hand unduly limit 100

the span of the fingers, so that long stretches as they appear in all greater compositions become impossible, or at least, extremely painful to the user of the hand. More than 5 that, such conditions greatly impede the finger work or finger dexterity, by which is meant that rapid, almost instantaneous up and down movement of the fingers and their almost as rapid spread, is almost constantly required. The condition of insufficient muscular strength prevents the fingers, hand, and arm from maintaining that position required for good tone work, speed, and massive playing, as is so often required; 10 but, on the contrary, produces toneless technique.

It is now noted that in compliance with musical nomenclature, I will in all cases in this specification denote the thumb as the 15 first finger; the index finger, as the second finger; the middle finger, as the third finger; the ring finger, as the fourth finger; and the little finger as the fifth finger.

The problem of correcting a faulty hand 20 into a good piano or violin hand, the faultless hand, as it were, resides entirely in permanently stretching or widening the hand and then increasing the muscular strength thereof. These are closely inter- 25 related to each other, and in the exemplification of my invention are provided all the essentials for correcting a hand, but it is absolutely necessary that the student himself 30 must of his own strength and endeavor per- 35 form the exercises hereinafter described in order to effect a permanent correction of the hand or hands.

Briefly then my invention resides in a 40 method of and means for correcting a faulty hand into one properly adapted for the playing of the piano or other stringed musical instrument. By the employment of my device I permanently widen the hand while the same is maintained in the correct play- 45 ing position, and it may now be stated that the proper position of a good hand in piano playing, is as shown in Fig. 2, in which the wrist is depressed or held low; the palmar surface at the joints of the first digit ele- 50 vated or held high; the first digit disposed in about a horizontal plane; the second digit at about an angle of 45 degrees from the same horizontal, and the third digit at a right angle to said horizontal, or in a position perpendicular to the keys to be struck.

Now to better explain my invention I believe it of greater advantage to first describe and disclose in detail my device in one of the preferred constructions thereof, (it being 60 understood that the mechanical details of many of the parts and elements of construction may be changed and altered at will without falling within the scope of my invention) and then explain in detail the 65 various functions of the device by means of

diagrammatic drawings, disclosing how these functions are performed by the means of the component parts of the structure.

In Figs. 1 and 2, 10 and 10^a are substantially rectangular vertical plates or members maintained in spaced apart, parallel relationship, and, connecting the upper ends of these members 10 and 10^a are bars 11, and 70 11^a likewise maintained in spaced apart parallel relationship, forming therebetween 75 a longitudinal slot 12 extending the full distance between said vertical plates. Projecting forwardly from the forward edge of bar 11^a are a plurality of horizontally protruding pins 13, the outer or free ends of which are 80 bent upwardly as at 13^b. These hooked pins are equally spaced along the edge of the bar 11^a and some of the same are longer than others as seen at 13^b. It is now to be noted 85 that the members 10 and 10^a, which are really the side frames of my device, and will be so termed hereafter, are connected together near their lower ends by a frame spreader rod 14, held in place by tap screws or bolts 15 and 15^a, the whole forming a well connected structure. 90

Fastened to and projecting horizontally from the side members 10 and 10^a are posts 16 and 16^a, which posts are possessed of through cross apertures, 17 and 17^a, preferably square, and extending in planes parallel to said side frames, but slightly upwardly toward the forward portions of the device, and, slidably fitted in these through apertures are sliding rods 18 and 18^a adapted to be held in fixed position by thumb screws 19 and 19^a, arranged in the posts 16 and 16^a. The sliding rods 18 and 18^a are adapted to slide in a slightly upwardly direction to a variable point forward of the front of the device and are supported from the stand upon which they may be located by short studs 20 and 20^a. At their outer ends these rods have perpendicular stems or standards 21 and 21^a, projecting from the forward faces of which are a series of equally spaced pins 22 and 22^a. Said sliding rods 18 and 18^a are connected together by a slideable blade or bar 23, which is adapted for free movement along said rods in the space extending between the edges of the frames 10 and 10^a and the upstanding studs 21 and 21^a, and, like the standards 21 and 21^a, and the frame top bar 11^a, are provided with a plurality of equally spaced forwardly and down- 110 wardly pointing hooks 23^a. 115

A short distance within the forward edge of the side frames 10 and 10^a, in corresponding situations in both frames, a proper distance above the common base thereof, 120 there are tapped holes for the reception therein of thumb screws 24 and 24^a, which screws are embraced by open ended long slots 25 located in forwardly projecting bars 26 and 26^a, the forward ends of which are con- 125 130

nected by a round, longitudinal shaft 27, extending the length of the device as a whole, and are fixed to said blades 26 and 26^a by machine screws 28 and 28^a. Freely revoluble 5 and laterally movable on the shaft 27 normally set medially of the length thereof are four concaved anti-friction rollers 29.

Located directly above thumb screws 24 and 24^a and in vertical alinement thereto 10 are tapped openings, in side frames 10 and 10^a, for the entrance therein of the threaded portions of handled thumb screws 30 and 30^a, which are embraced in slots 31 of blade members 32 and 32^a, and the outer ends of 15 these blade members have a connecting shaft 33, parallel to shaft 27, which former is fastened to the blades 32 and 32^a by screws 34 and 34^a or other equivalent means. Suspended from shaft 33 and oscillatable there- 20 on, approximately medially of its length thereof, is a built up member 35, which may be termed a backing for the wrist of a player whose hand is undergoing correction. This backing 35 possesses a sleeve 36, ro- 25 tatably and laterally movable on shaft 33 and may be fixed in position by a thumb screw 37. Depending from this sleeve at either end thereof are arms 38 and 38^a, which terminate in a backing plate 39, to 30 the under face of which is attached a felt or similar cushion pad 40.

Depending from the frame top bars 11 and 11^a and suspended by studs 41, passing through the slot 12, are four vertically disposed, oscillatable, wing plates, which being precisely alike, except as to being rights and lefts, are characterized by the character W. The studs 41, which are secured to these wings W, are slidable in the slot 40 12, and are adapted to be fixed in rigid position by wing nuts 42, and it is to be observed that one of the extreme and one of the mean studs 41 and wing nuts 42 are longer than the others, the purpose of which 45 is to permit the studs to be moved into adjacency with each other and yet allow the tightening up thereof by the longer and shorter wing nuts 42 in an evident manner.

Describing one of the wings W, the same 50 is of substantially rectangular contour, extending from the under side of the frame bars 11 and 11^a to within a short distance of the frame spreader rod 14 as seen in Figs. 3 and 5. Located on the top edge of 55 said wing near the rear corner thereof is a fixed circular flange 43, and centrally below the same is a protuberance 44, the latter for the purpose of receiving the lower end of the stud 41, and the former being 60 provided for a free sliding contact with the under side of bars 11 and 11^a, and also for presenting ample frictional area when the wing nuts 42 are tightly screwed up.

Fixedly attached to the rear edge of wing 65 W and extending downwardly and slightly

backwardly is a tubular member 45 having in its rear wall a slot 46 extending the entire length of said tube. Within said tube is a slidable plunger 47, adapted to receive the threaded end of a thumb screw 48, movable in the slot 46, with its head thereof bearing upon a friction washer 49, partially embracing tube 45 on either side of said slot. It will thus be observed, that the plunger 47 becomes freely movable in the 70 tubular member 45 by the easing off of thumb screw 48 and a tightening up thereof rigidifies said plunger in said tube.

Positioned a short distance from the lower, rear corner of the wing W and forwardly of the tubular member 45 is fixed a stud 50^a, which is attached to the wing W and about which is adapted to oscillate a bar 50. Said bar has a rearward extension 51 the rear end of which is offset as at 52, 80 so as to bring the same directly below the tube 45. In this tube is located a compression spring 53, with its upper end pressing against plunger 47 and its lower end embracing a short stud 53^b of a semispherical 85 member 53^a, which member is adapted for a slight sliding motion on said extension 52 as the bar 50 is oscillated. Bent from the wing W is a small projection 53^c, which is so arranged that when under the action 90 of the spring 53 the bar 50 reaches a horizontal plane it will be maintained there. In other words the stop 53^c will prevent any 95 uptilting of the forward end of the bar 50 beyond a horizontal plane. Near the front 100 of bar 50, in its top face, are produced tapped openings 54, for the alternate or successive reception of a stud 55 therein. It is now to be explained that the oscillatable bar 50 on the wing W bears the same 105 relationship to this device as does a key to a piano, and when inert lies in a horizontal plane, the same as in a piano. The action of the spring 53 tends to impel the outer 110 end 56 of the bar upwardly, while the medial finger sketched in Fig. 5 tends to depress the key. The finger pressure required for such depression may be varied by changing the relative location of the plunger 47 in the tube 45 in a manner readily comprehended.

Before I go into further detail as to how a faulty hand is corrected, I must again emphasize the fact that a permanent widening of the hand can only be accomplished 120 with the fingers and hand in correct playing position as already described. This understood, I first place the 2nd, 3rd, 4th, and 5th fingers upon the keys 50 with the tips of said fingers against the stop pin 55. 125 Then with the fingers in proper curved position, I adjust shaft 27 to the proper elevation of the palm, with the convexed sleeves 29 under the palmar joints of the last four fingers, and fasten this shaft in position 130.

through the media of the thumb nuts 24 and 24^a. Next I depress the shaft 33 with the wrist backing 35, until the latter forces the wrist downwardly to its proper position 5 and fix that shaft in position. The fingers, hand, and wrist are now supported in correct playing position. Next I move the wing W against the fourth finger and physically force it away from the third by moving and oscillating the said wing against 10 said forth finger. It will be noticed that as the wing W extends beyond the second joint of the finger toward the palmar joint, that the stretch as it were must result in 15 an increase of the distance between the palmar joints and metacarpals. The wing for the fourth finger is then fastened in place and the wing for the fifth finger is applied to widen the space between the 20 fourth and fifth palmar joint. The wings W are also directed to the 2nd and 3rd fingers, to widen the space between the second and third joints, and it will now be seen that each of the four fingers is 25 confined in a stretched apart position in an approximation of the position of a correct hand and that the spread of the four fingers is what they ought to be, and that each finger is in its proper curved playing position 30 with the palmer joints high and the wrist low. The springs 53 on the wings W are now adjusted to a proper degree to exert a resistance to depression of the keys by the fingers thereon. Lastly I slip a ring 35 100 over the first finger or thumb near the first joint thereof and draw tightly on the ring and its tensioning means 101, 102, and 103 to draw or pull the thumb palmar joint away from the same joint of the second finger, so as to increase the distance between 40 the thumb and second finger, and likewise the spread between the thumb and last finger. The student now moves the second finger in an up and down movement depressing 45 the key 50 at each downward motion until the finger becomes tired, or in from one to two minutes. The third, fourth, and fifth fingers are then likewise exercised, and attention is drawn to the fact, that the muscles 50 in the palm and around the joints are caused to become pliable and flexible, so as to enable the palmar joints to permanently settle in their now widened apart position. These exercises are repeated day after day 55 for weeks until the new location of the joints becomes a natural one. The thumb is likewise moved in an upward and downward direction, and that motion in connection with the steady strain upon the same caused by the ring 100, and its spring 103 hooked over the hook 22, likewise causes 60 the separation or widening away of the thumb palmar joint from that of the second finger.

Attention is now drawn to the fact that 65 rings 70 with their faces 71 are slipped over the fingers before the wings are forced against them so that skin abrasion of the fingers during the upward and downward movement is avoided. 70

In order to increase flexibility and elasticity of the muscles joining adjacent fingers and at the same time strengthen the same, the following exercise takes place: After the so called spreading exercise: The second 75 finger is maintained in elevated relationship by the yielding band 104 and chain 105 hooked over pin 13. The third finger is now moved up and down as before, whereby the 80 muscles and ligaments between it and the first finger are rendered flexible and strengthened. The third finger may then be held elevated and the second and fourth are moved up and down thereby loosening, and strengthening and flexing the muscles and ligaments between the second and third and the third and fourth. The fifth finger may be elevated and the fourth moved up and down, to flex, and strengthen the muscles between the fourth and fifth. In fact any 85 combinations of fingers may be elevated and the others exercised, the total result of which is the strengthening of each finger and eliminating entirely the generally existing 90 and sympathetic movement of the other fingers than the one moved. It is to be understood that these exercises extend into the 95 muscles of the entire palm, wrist, and forearm as well, rendering the same flexible, strong, and instantaneously responsive to 100 cerebral directions. To further increase the strengthening of these muscles and to render the individual fingers more independent of 105 each other when acting in an upward and downward movement, the exercise disclosed in Fig. 5 is directed, in which, for instance the second finger is forcibly maintained in a 110 depressed position, even to the limit of movement of the key 50, by means of the band 104 and chain 105, the latter being hooked over the proper hook 23^a of lower cross bar 23. In this exercise the third finger is free for up and down movement, and the fourth finger is maintained in an elevated position, 115 as already described and shown in Fig. 5. In this way the up and down movement of the intermediate finger affects and strengthens the muscles to either side thereof, and it is to be understood that any desired combination of the fingers as just described may 120 be made to effect the desired result. The muscles in the wrist and forearm often require strengthening and flexing in addition to that derived from the other exercises, and for this particular exercise I clamp the arm 125 near the wrist between the shafts 27 and 33 and instruct the student to physically move the hand up and down by the muscles of the

forearm and arm. This exercise is continued periodically as are all the others herein mentioned until the desired result is effected. When approximately below the palmar joint 5 of the fifth finger the thumb must be capable of vertical movement, as in striking keys, without any visible movement of any of the other fingers or parts of the hand. To attain this result the spring 103 is transferred to the opposite pin 22^a, the thumb pulled in the opposite direction under the palm, and the up and down movement instituted and periodically continued until the desired result is effected.

15 In many cases it is found that the muscles between the joints of a finger or fingers are not strong enough to withstand the striking of the keys and break down as it were. To correct this evil the exercises 20 shown in Figs. 15, 16, 17, and 18 are instituted. In Fig. 15 is indicated the development of the flexor muscles of the third joint; while in Fig. 16 the strengthening development of the extensor muscles of the same 25 joint are disclosed, and the same may be said of the second joints of a finger as seen in Figs. 17 and 18.

In conclusion I now state that an industrious and ambitious student possessed of 30 faulty hands may by hard work, extending over several years of time and labor, overcome to a certain extent the shortcomings of his faulty hands, but not entirely so, while with the assistance of my invention, 35 his hands will be entirely corrected in a period of some six to eight weeks. I further wish to finally emphasize that hereinbefore I have mainly shown my device as corrective of faulty hands for the piano; the 40 same remarks apply equally well to any stringed instrument where dexterity of finger work, spread of fingers, or pressure of contact with keys or strings is an essential.

I have hereinbefore disclosed the preferred mode of practising my invention, but I reserve the right to make such and any changes as might occur to one skilled in the art to which this invention appertains, or to make any and all such alterations as may 50 be permitted under the doctrine of equivalents.

Having thus fully described my invention I claim as new, and desire to secure to myself by Letters Patent of the United 55 States:—

1. An apparatus of the class described, comprising individual supports for each finger of a hand, means for separating said supports to spread the fingers, and means 60 for maintaining said supports in separated position.

2. In an apparatus of the class described, a frame, wings in said frame, there being finger supporting bars in connection with

said wings, finger stop pins on said supporting bars, and a rest for the palmar joint of the hand, whereby the fingers thereof are maintained in a properly curved position.

3. In an apparatus of the class described, a frame, wings in said frame, there being 70 movably mounted finger supporting bars in connection with said wings, finger stop pins on said supporting bars, and a rest for the palmar joint of a hand, whereby the fingers thereof are maintained in a properly curved 75 position.

4. In an apparatus of the class described, a frame having side members and connecting bars between said side members, finger spreading wings in connection with said 80 bars, finger supporting bars in connection with said wings, and means maintaining the fingers in a curved position.

5. In an apparatus of the class described, a frame having side members and connecting 85 bars between said side members, finger spreading wings in connection with said bars, finger supporting bars in connection with said wings, and means maintaining the fingers in a curved position, and independent tensioning means for the fingers, supported from the frame.

6. In an apparatus of the class described, a frame, a wrist backing in said frame, a plurality of individual supports for four 95 fingers of a hand in said frame, and a yielding support for the thumb extending from a part of said frame.

7. In an apparatus of the class described, a frame, a wrist backing in said frame, a 100 plurality of individual supports for four fingers of a hand in said frame, finger spreading wings interposed between the fingers and attached to the individual supports, and a yielding support for the thumb 105 extending from a part of said frame.

8. An apparatus of the class described, comprising a frame, a support for the palmar joints of the fingers of a hand, individual supports for the four fingers of the 110 hand, means for separately maintaining the said four fingers in a downwardly curved position, and means for spreading said fingers.

9. An apparatus of the class described, 115 comprising a frame, a wrist backing in said frame, a support for the palmar joints of a hand arranged in front of said wrist backing, individual supports for the four fingers of the hand arranged in front of the support for the palmar joints, means connected to said individual supports for spreading the fingers, and means for maintaining the said four fingers in a downwardly curved position.

10. An apparatus of the class described, 120 comprising a frame, a wrist backing in said frame, a support for the palmar joints of a

hand arranged in front of said wrist backing, said support being adjustable, individual supports for the four fingers of the hand arranged in front of the support for the palmar joints, means connected to said individual supports for spreading the fingers, and means for maintaining the said four fingers in a downwardly curved position.

11. In an apparatus of the class described, 10 a finger support comprising an oscillatable bar, and a spreading wing attached to the side of said bar.

In testimony that I claim the foregoing as my invention, I have hereunto set my 15 hand.

VICTOR HEINZE.
